UNITED STATES PATENT OFFICE.

WALTER C. SMITH, OF PHILADELPHIA, PENNSYLVANIA.

TELEGRAPH-SOUNDER.

SPECIFICATION forming part of Letters Patent No. 288,881, dated November 20, 1883.

Application filed February 24, 1883. (No model.)

To all whom it may concern:

Be it known that I, WALTER C. SMITH, a citizen of the United States, residing at Philadelphia, in the county of Philadelphia and 5 State of Pennsylvania, have invented a new and useful Improvement in Telegraph-Sounders, of which the following is a specification.

My invention consists of an arched housing, which has an arm projecting from the arch for 10 the connection of the regulating-screw of the tension-spring connected with the sounding-lever, as hereinafter described.

In the accompanying drawings, which make a part of this specification, Figure 1 is a plan 15 view of my improved instrument. Fig. 2 is side elevation of the same. Fig. 3 is a rear end view of the instrument.

Like letters of reference in all the figures indicate the same parts.

20 In my improved instrument, A represents a housing of arch form, having an arm, b, projecting from its rear side, which is tapped to receive the vertical screw B. C is the sounding-lever; D, the tension-spring for regulating the lever, which is hung on fulcrum-points 25 of screws which pass through the uprights of the housing A, one end of the spring being

connected with the rear end of the lever, as seen in Figs. 2 and 3, and the other end with the end of the screw B. E is the armature, 30 and F F the magnets.

With the exception of the construction of the housing A with the arm b, as above described, the instrument is substantially like other instruments. The arm is, however, an 35 essential feature when the lever C is hung, as described, by its fulcrum-points held in the uprights of the housing, as it gives practicability to placing the screw at a suitable distance in the rear of the vertical plane of the 40 fulcrum-points to secure the proper action of the tension-spring D in the simplest manner and in a convenient place for the operator.

I claim as my invention—

The arch A, having rear arm, b, carrying 45 regulating-screw B, in combination with the lever C, pivoted as described, and tension-spring D, connecting the lever and regulating-screw, substantially as described.

WALTER C. SMITH.
